UNITED STATES PATENT OFFICE.

HENRY JOHN CHART, OF RICHMOND, ENGLAND.

APPARATUS FOR ADVERTISING OR THE LIKE.

SPECIFICATION forming part of Letters Patent No. 774,647, dated November 8, 1904.

Application filed March 22, 1904. Serial No. 199,466. (No model.)

To all whom it may concern:

Be it known that I, HENRY JOHN CHART, gentleman, a subject of the King of Great Britain and Ireland, residing at 7 Dynevor 5 Gardens, Richmond, in the county of Surrey, England, have invented certain new and useful Improvements in Apparatus for Advertising or the Like, of which the following is a specification.

- 10 The object of my invention is to improve the construction of that class of advertising devices in which there are a series of designs properly isolated one from another and before which the observer passes rapidly, as in 15 a railway-train, so that the succession of figures portrayed and the words of the advertisement may be presented to the eye clearly, distinctly, and properly positioned, so as to produce a pleasing impression.
- 20 The above object I accomplish by forming each individual box or unit of the series with a narrow vertical slit of much less width than the design which is placed behind it and by 25 horizontally contracting the representation of the design. The figures and reading matter may be similar on the several boxes to create an impression of a single advertisement, or the figures may vary slightly to produce the impression of a moving picture, as is well known 30 in the art.

In the accompanying drawings, Figure 1 is a front view. Fig. 2 is a vertical transverse section. Fig. 3 is a horizontal section of one 35 of my improved boxes. Fig. 4 is a front elevation in section of a number of such boxes.

The boxes are provided with the aforesaid slit *a*, illuminating means *b*, and the advertisements *c*, while a figure (in varying positions in successive boxes or compartments to 40 give the appearance of motion) is shown at *d*, it being understood that if the boxes or compartments contain instead of or in addition to the advertisements or the like a series of figures or pictures presenting in each succeeding 45 box or compartment the successive positions assumed in any action these will appear to the observer as a moving picture or pictures. The advertisements or the like or the said figures or pictures, or both, can be applied 50 to the backs or sides or either of the sides or

to both the back and sides or either of the sides of the interior of the boxes or compartments. The vertical components of the letters, devices, figures, or pictures constituting the advertisement or the like should be somewhat narrowed laterally, and the horizontal components should be contracted horizontally and broadened vertically in order that the letters, devices, figures, or pictures may appear in the desired proportions to the observer. 55

The device may be placed in any position in which the lighting effect within the boxes or compartments so far exceeds the light there may be outside that the advertisements or the like in the boxes or compartments will be 60 visible through the slits. For instance, the boxes or compartments may be placed in the windows of shops or on walls or boardings, along pathways or roadways, or they may be placed on the walls of the tunnels of rail- 65 ways, so that the advertisements or the like are visible to passengers in trains passing through the tunnels, and in this case the illumination of the interiors of the boxes or compartments may be effected by electric 70 lamps which can be switched on and off at the requisite times by a device operated by the passing train.

Although the boxes or compartments may be close together, yet in practice and for the 75 sake of economy they may be at a distance apart varying with the speed at which the observer may be supposed to pass. The quicker the observer passes the greater may be the distance apart of the boxes or compartments, 80 as it will be understood that the image from each succeeding box or compartment should be received by the retina of the eye of the observer before the image from the preceding box or compartment has faded from the 85 retina. For example, when the device is used in a railway-tunnel and the train may be presumed to travel at that place at the rate of about fifteen miles an hour the boxes will 90 give a good effect to passengers in the train 95 if the said boxes be arranged about four feet apart. It is preferred to slope the front part of the box outward from each side to the slit, as this will prevent the thickness of the material at the slit interfering with the vision, 100

while when thin material is used it will strengthen the front and preserve the parallelism of the sides of the slit.

I do not limit myself to the proportions of the box shown, as they may be made to suit the position in which the boxes or receptacles are placed and the depth may vary with the distance from which the series is to be observed or with the degree of horizontal contraction given to the advertisements, figures, or the like in the boxes or receptacles. The slit *a* should be made sufficiently narrow to give a clear definition. About the one-sixteenth of an inch is a suitable width for the said slit *a* in the instance illustrated; but I do not limit myself to this.

I claim as my invention—

An advertising device, consisting of a series of isolated designs with a box or compartment for each unit design having a closed front with a narrow vertical slit, the unit designs having their vertical components narrowed laterally and the horizontal components contracted horizontally and broadened vertically.

In testimony whereof I have signed my name to this specification in the presence of two subscribing witnesses.

HENRY JOHN CHART.
